UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE FOR CASTING TUBULAR STEREOTYPE PRINTING PLATES.

Original application filed April 19, 1921, Serial No. 462,733. Divided and this application filed December 13, 1924. Serial No. 755,767. Renewed July 5, 1928.

This invention relates to a mold for producing tubular stereotype printing plates, namely, plates which constitute practically a complete circle as distinguished from the ordinary semi-cylindrical plates. These plates substantially cover the entire cylinder of a press and are formed originally in their complete cylindrical condition. They are removed from the mold by turning the core which is provided with a helical groove forming a corresponding helical rib on the inside of the plate.

The principal objects of this invention are to provide improved means for operating the core for the purpose of ejecting the casting; to provide for the casting of continuous ribs on the plate extending across the gap which is to be provided, and means for automatically cutting off these ribs across the gap; to provide simple and convenient means for holding the casting box either in its vertical position for receiving or in its horizontal position for delivering; and to provide improvements in the mechanism for operating the core.

Further objects and advantages of the invention will appear hereinafter.

Reference is to be had to the accompanying drawings in which

Fig. 1 is a plan of a casting box constructed according to this invention;

Fig. 2 is a side view of the same in horizontal position;

Fig. 3 is a side view of part of the box in horizontal position with the supporting shaft in section to illustrate the cam for operating the clutch for starting the core;

Fig. 4 is a side view on an enlarged scale, and partly in central section, of the casting box in upright position ready for pouring;

Fig. 5 is a still further enlarged sectional view of the bottom of the mold cavity;

Fig. 6 is a sectional view of the plate cast therein showing the ribs across the gap;

Fig. 7 is a sectional view of the device for cutting off the ribs;

Fig. 8 is a transverse sectional view of the casting box on the line 8-8 of Fig. 1 showing the cooling chambers;

Fig. 9 is a view of the delivery end of the casting box;

Fig. 10 is a longitudinal central section of

the lower end of the casting box showing the water circulating system; and

Fig. 11 is a transverse sectional view on the line 11-11 of Fig. 10;

The casting box 15 is mounted on a frame 13 which is provided with two bearings for trunnions 14 projecting from the sides of the box 15. The box is provided with longitudinal pivots 16 and with a cover 17 which is adapted to be opened for the insertion of the matrix M. This cover is secured to the bottom of the box by a pivoted lever 18 engaging a pin 19.

The casting chamber consists of the cavity 65 between the two parts 15 and 17 of the casting box and a core C of full cylindrical form rotatably mounted therein and provided with a continuous helical groove e' in its surface. The usual matrix and head ring H are provided and also the pouring sheet S at the outer end of the box. The straight edges of the matrix are held in slits along the sides of the margin bar B which extends all the way across the mold cavity and throughout its 75 length.

The box being closed and in condition for casting, it can be turned from the horizontal position shown in Figs. 1 and 2 into the vertical positions shown in Fig. 4. This is the 80 casting position.

Fixedly mounted with respect to the frame 13 on each side is a cam 23 having two surfaces on which a roller 21 is adapted to rest. This roller is mounted on a pivoted arm 22 85 and held against the cam by a spring 27. The cam 23 being stationary, it will be understood that upon the rotation of the box from horizontal to vertical position the relation of the cam to the roller 21 will change from that 90 shown in Fig. 3 where the box is horizontal, to that shown in Fig. 4 where it is vertical.

Pivoted to the arm 22 is a link 24 and these parts are duplicated on the two sides of the machine. These links have perforated ends 95 25 which receive the ends of a pair of studs 26 projecting through slots 28 in the end cap 30 of the mold. These studs 26 are bolted to projections on a clutch ring 31 which is slidably mounted on a hub 32 inside the end cap. 100 This hub is rotatably mounted on a cylinder 33 which constitutes the end of the core C in

the mold. The clutch ring is provided with a pair of longitudinal pins 35 each extending through slots in a loose gear 36.

The springs 27 normally force the clutch ring 31 and the pins 35 to the left in Fig. 10. The ends of these pins bear on the flat surface of a circular plate 38 which is bolted to the end plate 39 of the mold proper and which in turn is bolted to the cap 30. On the end 10 of this cap is a hollow plate 40, the end of which is sealed by a packing. These parts 38, 39, 40 and 30 constitute a single element, therefore, containing a chamber and receiving some of the mechanism above described.

15 The face of the plate 38 is provided with two depressions or notches 41 for receiving the pins 35. Obviously if the gear 36 is rotated when the arms 22 are swung over into the left hand position, that is, when the 20 mold is horizontal, these pins 35 will spring into the notches 41 and take up the structure, 38, 39, 40 and 30 and rotate it. Furthermore, the plate 38 is keyed to the cylinder 33 and therefore the core will rotate with it. The 25 mold 15, however, is not a part of the rotary mechanism.

It may be stated at this point that the operating mechanism is driven by a sprocket chain 42 or any other desired device acting 30 on a sprocket wheel 43 which is fixed to a sprocket wheel 44, the two of which are freely rotatable on one of the trunnions 14. From the sprocket wheel 44 a chain 45 drives a sprocket wheel 46 on the end of a shaft 47. 35 On this shaft 47 there is a worm 48 meshing with the worm wheel 36 and driving it constantly. As these parts rotate around the trunnions 14 as a center this rotation can be kept up at all times if desired while the casting is being made, or it can be controlled to start it when desired. In either event the worm wheel 36 rotates idly until the pins 35 engage in the notches 41 and then the core will be rotated.

45 The helical groove extends around and along the core and a continuous helical rib, therefore, is produced on the casting. The result of this rotation of the core, while the outside of the casting box is held stationary, 50 is to force the casting in a rectilinear direction out of the end of the box. Although the margin bar B provides a longitudinal marginal opening throughout the length of the plate P, the helical grooves on the core are 55 continuous and they cause connecting ribs R to be cast on the plate P projecting across the margin gap or opening. The ribs therefore are continuous. As the plate P is moved forward these ribs are cut off by a knife 50 secured to the bracket 51 which is attached to the outside of the box and constitutes a support and bearing for the upper and outer end of the core.

In the casting of the plate, starting with 60 the box in horizontal position, the hinged

cover 17 of the casting box is thrown open and the matrix placed in position against the head ring H. It is bent circumferentially and its straight edges engage the margin bar B which extends throughout the length of the casting chamber. The pouring sheet S is then put in place overlapping the circular end of the matrix. The hinged cover 17 is closed and locked in position by the lever 18 and then the box is swung up into vertical 70 position. Metal is then poured into the box. Power is turned on in any desired way so that the chains 42 and 45 will be started. This rotates the wheel 36. When the box has reached horizontal position the rollers 21 on the two sides fall into recesses on the cans 23. The springs 27 swing the arm 22 over to the left and bring with them the clutch ring 31 which holds the pins 35 yieldingly against the surface of the plate 38. As soon as the 80 pins 35 come into registration with the notches 41 the springs 27 force these pins into the notches and thereafter the cap end of the mold and core C are rotated positively by the chains.

90 On account of the helical grooves in the core and the fact that the plate is held firmly by the margin bar B, the rotation of the core will start the plate out of the box longitudinally with the matrix thereon. During this motion of the plate forward the ribs are cut through the margin opening by the knife 50 as stated.

This is a division of my application on a machine and plant for casting and cooling 100 tubular stereotype printing plates, filed April 19, 1921, Serial No. 462,733, patented January 6, 1924, No. 1,521,849, and I do not claim herein the matter claimed in that case.

105 Although I have described and illustrated only a single form of the invention I am aware of the fact that modifications can be made therein by any person skilled in the art without departing from the scope of the invention as expressed in the claims. Therefore, I do not wish to be limited to all the details of construction or the relative arrangement of parts therein shown and described, but what I do claim is:—

110 1. In a stereotype plate casting device, the combination with a casting box mounted to swing from upright to horizontal position on a horizontal axis, of means for automatically ejecting the casting longitudinally from the box when it is turned down to horizontal 115 position.

120 2. In a casting device, the combination of a box, a rotatable core therein having a helical groove on its exterior surface for casting a corresponding rib on the interior of the plate, means for supporting said box on trunnions so that it can move from one position to another, and means for starting the core to rotate for ejecting the casting automatically when the box is turned to one position. 125 130

3. In a stereotype plate casting device, the combination of a tubular box, a rotatable core therein having a helical groove on its exterior surface for casting a corresponding rib on the interior of the plate, means for supporting said box on horizontal trunnions so that it can move from upright to horizontal position, a wheel freely rotatable in the mold box and positively driven, a clutch ring having pins projecting through said wheel and fixedly connected with the core, a plate having notches for receiving the ends of said pins, yielding means for forcing said clutch ring inwardly to project the pins into the notches when they come into registration, and positive means for holding the clutch ring back except when the casting box is turned down to horizontal position and then permitting the yielding means to act.

4. In a stereotype plate casting machine, the combination of a supporting frame, a casting box having horizontal trunnions carried by said frame on which the box is adapted to swing from vertical to horizontal position, a stationary cam on one of the trunnions, and means controlled by said cam for starting to eject the plate when the box is turned to horizontal position.

5. In a stereotype plate casting device, the combination of a tubular box, a rotatable core therein having a helical groove on its exterior surface for casting a corresponding rib on the interior of the plate, means for supporting said box on horizontal trunnions so that it can move from upright to delivering position, a rotary wheel, positive means for connecting said wheel with the core to rotate the core, yielding means for actuating said positive means, and cams mounted on said trunnions in stationary position for preventing the action of said yielding means at all times until the mold is turned down to delivering position.

6. In a stereotype plate casting device, the combination of a box, a rotatable core therein having a helical groove on its exterior surface for casting a corresponding rib on the

interior of the plate, means for supporting said box on horizontal trunnions so that it can move from upright to horizontal position, a wheel freely rotatable in the mold box and positively driven, a clutch ring having pins projecting through said wheel and fixedly connected with the core, a plate having notches for receiving the ends of said pins, yielding means for forcing said clutch ring inwardly to project the pins into the notches when they come into registration, and positive means for holding the clutch ring back except when the casting box is turned down to horizontal position and then permitting the yielding means to act.

7. In a stereotype plate casting device, the combination of a tubular box, a rotatable core therein having a helical groove on its exterior surface for casting a corresponding rib on the interior of the plate, a wheel freely rotatable in the mold box and positively driven, a clutch ring having pins projecting through said wheel and fixedly connected with the core, a plate having notches for receiving the ends of said pins, yielding means for forcing said clutch ring inwardly to project the pins into the notches when they come into registration, and positive means for holding the clutch ring back except when the casting box is turned down to horizontal position and then permitting the yielding means to act.

8. In a casting box, the combination of a semi-cylindrical box and a semi-cylindrical cover pivoted together to form a complete cylindrical mold cavity, of a cylindrical core therein having a continuous helical groove on its surface extending from end to end and a longitudinal matrix bar contacting with the cylindrical surface of the core and under which said grooves extend, and means for ejecting the casting from the box without raising said cover.

In testimony whereof I have hereunto affixed my signature.

HENRY A. WISE WOOD.
